UNITED STATES PATENT OFFICE.

JONAS NORTHRUP, OF HOPEDALE, MASSACHUSETTS, ASSIGNOR TO HOPEDALE MANUFACTURING COMPANY, OF HOPEDALE, MASSACHUSETTS, A CORPORATION OF MASSACHUSETTS.

AUTOMATIC LOOM.

1,259,768.

Specification of Letters Patent. Patented Mar. 19, 1918.

Application filed November 26, 1913. Serial No. 803,224.

To all whom it may concern:

Be it known that I, JONAS NORTHRUP, a citizen of the United States, residing at Hopedale, in the county of Worcester and

5 State of Massachusetts, have invented certain new and useful Improvements in Automatic Looms; and I do hereby declare the following to be a full, clear, and exact description of the invention, such as will enable others skilled in the art to which it appertains to make and use the same.

The present invention relates to an improvement in automatic looms. The object of the invention is to reorganize and improve the construction of the automatic loom in certain details hereinafter referred to, for the purpose of improving its operation, simplifying its construction and for producing a construction particularly adapted to attachment to existing plain looms, whereby such looms may be made automatic.

To the above end the invention consists in the improvements hereinafter described and particularly defined in the claims.

In the accompanying drawings illustrating the preferred form of the invention as attached to a plain loom, Figure 1 is a front elevation of a portion of the loom; Fig. 2 is a front elevation of the hopper and associated parts; Fig. 3 is a sectional elevation of a part of the hopper and transerrer mechanism with the parts in the positions which they occupy when a new bobbin is about to be inserted in the shuttle, filling absence having been indicated on the opposite end of the loom; Fig. 4 is a similar view showing the parts in the positions which they occupy after a new bobbin has been inserted in the shuttle and before the feed of the hopper has been effected by the feed pawl; Fig. 5 is a view similar to Fig. 4 with the transerrer removed so as to show the feed and detent pawls; Fig. 6 is a section on the line 6—6 of Fig. 5, the hopper plate being shown in section and the other parts in elevation; Fig. 7 is a view similar to Fig. 3, showing the parts in the positions they assume after the feed of the hopper following a bobbin transfer; Fig. 8 is a section on the line 8—8 of Fig. 7; Fig. 9 is an elevation similar to Fig. 3 showing the position of the parts while the hopper, when empty at the bottom, is being racked for-

ward step by step to bring a bobbin to position for transfer to the shuttle; and Fig. 10 is an end elevation of the hopper plate from the loom side.

The illustrated embodiment of the invention is described as follows:

The hopper, indicated in a general way by the reference character H, is mounted on the right hand end of the breast beam B. The breast beam B is supported by the end frames F, the upper portions only of which are shown. The knock-off lever is indicated at K. The picker sticks are indicated at P. The temples are shown at T, and the filling detector device D mounted upon the breast beam on the left hand side of the cloth is connected by the usual rock shaft with the hopper mechanism on the right hand side of the loom. This rock shaft 1 is supported in brackets on the frame of the loom and provided with a spring 2 normally tending to turn it in the direction to cause the detector arm 3 and hopper arm 4 to move toward the breast beam (see Fig. 10). The filling detector D may be any usual or suitable form of detector for indicating filling absence. The hopper mechanism is mounted on the hopper plate 5, being provided with a bracket slot 6 which receives the bracket plate 7 of the bracket 11 bolted on the breast beam B of the loom. The bracket plate 7 is slotted, and bolts 12 are employed to secure the hopper plate to the bracket plate 7. The adjusting bolt 13 is screwed through an ear 14 on the plate 5 and engages the top of the bracket plate 7. It is secured in place by a lock nut and affords means, when the bolts 12 are loosened, to adjust the hopper plate 5 to correct vertical position. Horizontal, longitudinal and transverse adjustment of the hopper mechanism are secured by providing the foot of the bracket 11 with longitudinal slots and the breast beam with transverse slots through which the bolts pass, securing the bracket to the breast beam.

It will be recognized as of importance to adjust the hopper to the loom, as its proper positioning with relation to the lay is required in order to secure its coöperation with the shuttle. The means which are provided for this purpose form the subject-matter of United States Letters Patent No. 1,142,725, granted to me June 8, 1915.

BEST AVAILABLE COPY

The right hand picker stick P is guided in the usual manner in the slot in the lay. The bobbin chute 15 consists of a casting secured to the lay provided at its right hand end with a support 16 for the picker stick stop 17. The picker stick stop 17 consists of a casting having a leather face 20 secured thereto mounted on the picker stick stop support 16 and secured in place by means of a bolt 21 which clamps the stop to the support. The support is diagonally slotted at 22 and by loosening the bolt 21 and raising the stop, the operative face of the stop is moved to the left so as thereby to arrest the picker stick farther to the left. The position of the stop determines the position of the shuttle, and inasmuch as it is necessary that the shuttle should occupy a certain and definite position with relation to the transferer when the bobbin is inserted, the necessity for this adjustment is obviously imperative. Heretofore, the stop has been adjusted by additions or subtractions of material and the capacity for nice adjustment has not been had. It is to be observed that the picker wears in use, and the adjustment of the picker stick stop affords provision for compensating for such wear. The transferer for supplying new bobbins to the shuttle upon the exhaustion of the bobbin in the shuttle, or upon the breaking of the thread, consists of means which operates to engage a bobbin, drive it out of the hopper and into the shuttle. The transferer 30 has a stud 30 carried by the transferer arm support 31 mounted upon the inner end of hub 36, which, in turn, is loosely supported upon the transferer stud 33 mounted in the hopper plate 5. A coil spring 34 acts normally to support the transferer hub 36 in the position shown in Fig. 3. The transferer is provided with a latch operating arm 35 to which the latch 36 is pivoted. When the latch 36 is lifted to the position illustrated in Fig. 3, it will be engaged by the bunter 37 on the next forward movement of the lay and thereby operate the transferer to push a bobbin out of the machine and into the shuttle. The latch 36 is provided with a pin 38 which engages the slot 39 in the end of the latch lifting arm 41 mounted upon the latch lifting stud 33 and also pivoted upon the stud 33 on the opposite side of the hopper plate 5. The hub 36 carries the lifter operating arm 41 between the latch lifter is swung forward to the position shown in Fig. 9 to the position shown in Fig. 3, it lifts the latch into position to be struck by the bunter 37. The lifter 41 is connected with the hopper arm 4 by means of the spring 44 which is of a plastic or yielding construction between the hopper arm 4 and the lifter operating arm 41. Owing to the elasticity of this spring it will be seen

that the hopper arm 4 may be swung to the left, as shown in Fig. 3, without causing the lifter operating arm 43 to be pulled thereby to the left, in case it is prevented from such movement, by virtue of the yielding of the spring 44. The spring 44 is attached to the pin 45 on the extension plate 46 mounted upon the upper end of the hopper arm 4. The extension plate 46 is slotted at 47 and adjustably secured upon the upper end of the hopper arm by the bolt 48. A lateral projection on the extension plate 46 has an inclined end which engages the surface of the boss on the end of the lifter operating arm 43 and preserves a normal relation between the two, which may be changed owing to the elasticity of the spring 44 when the occasion requires.

The lifter operating arm lifts the latch on the indication of filling absence and throws the shuttle feeler forward into feeling position, then when the lay beats up, if the shuttle occupies its correct position in the right-hand shuttle box, the feeler does not engage the shuttle and the latch is struck by the bunter on the lay, thereby causing an insertion of a new filling supply in the shuttle. But if the shuttle is not correctly boxed, it engages the feeler, and, through the connections between it and the latch, it depresses the latch, so that it is not struck by the bunter on the lay. This feeler mechanism is described as follows:— The feeler 50 mounted on the lower end of the feeler arm 51 pivoted at 52 on the hopper plate 5, is provided with an upwardly extending arm 53 having a hole 54 in it which receives a pin projecting laterally from the adjusting nut 55 which receives the link 56 by which the feeler arm is connected with the arm 43 mounted on the transferer stud 33.

The above described arrangement is such that when filling absence is indicated by the filling detector D, the detector arm 3 is operated by the detector D to oscillate the rock shaft 1 so as to swing the hopper arm to the right, as viewed in Fig. 10, thereby exerting a pull upon the spring 44 and causing it to oscillate the shuttle feeler to swing into feeling position. If when the lay beats up the shuttle is properly boxed, the feeler is not engaged by the shuttle and the latch 36 is engaged by the bunter 37 on the lay and the transferer is thereby operated to insert a new filling supply in the shuttle. If, however, the shuttle engages the shuttle feeler, it oscillates the feeler in the direction to cause a pull to be exerted upon the link 56 thereby turning the arm 43 and the arm 41 so as to drop the latch 36 out of the path of movement of the bunter, so as thereby to prevent the operation of the transferer mechanism.

The hopper is advanced to bring the bob-

bins into position to be fed into the shuttle by the feed pawl 60 and its actuating mechanism. The feed pawl is provided with a tooth 61 adapted to engage the ratchet 62 on the side of the butt-end disk 63. Opposite the dog 61 is a lug 64 which is adapted to engage the inside of the ratchet 62 so as to prevent the feed pawl from being moved too far to the left. The feed pawl 60 is also provided with a right-angled hand hold 65 which is adapted to be engaged by the hand of the operative for withdrawing the tooth 61 from engagement with the ratchet 62 (the lug 64 limiting this withdrawing movement) when it is desired to turn the hopper backward for any reason. The shape of the feed pawl 60 is illustrated in Fig. 5, which represents the parts in the same position as that in which they are shown in Fig. 3 but with the transferrer and transerrer latch removed. The feed pawl is provided with an opening 66 which receives the end of the arm 67 of the feed pawl operating lever 70 pivoted at 71 upon the hopper plate 5. The feed pawl operating lever 70 is a bell crank lever of which the arm 67 is substantially horizontal and the other arm 72 substantially vertical. The vertical arm 72 carries at its lower end a feed latch 73 which constitutes one arm of the feed latch lever 74 pivoted at 75 upon the vertical arm 72 of the feed pawl operating lever 70. The vertical arm 76 of the feed latch lever is adapted to engage the face 77 of the abutment stand 78, when the feed pawl operating lever 70 occupies its advanced position, as indicated in Fig. 7. The feed pawl 60 is provided on its under side with a projection 79 encircled by a spring 80 which engages the upper face of the abutment stand 78 and normally tends to move the feed pawl 60 in the direction to cause it to advance the hopper, that is, to feed the hopper forward to bring a new bobbin into position to be inserted in the shuttle. By reference to Figs. 5 and 7 it will be observed that the feed pawl operating lever 70 and the feed pawl 60 are so articulated together that the movement of the one will cause the movement of the other, thus, when the feed pawl is advanced by the spring 80 to feed the hopper, the feed pawl operating lever 70 will be swung to the position illustrated in Fig. 7, thereby bringing the feed latch 73 into the position indicated in Fig. 7 ready to be struck by the bunter 37 on the lay. When the bunter 37 on the lay strikes the feed latch 73, it causes the feed pawl operating lever 70 to be turned to the position indicated in Fig. 5, thereby lowering the feed pawl, compressing the spring 80, and bringing the feed pawl to the "set" position indicated in Fig. 5. Upon the retraction of the bunter 37 from engagement with the feed latch 73, the latter falls to the position

shown in dotted lines in Fig. 7, and upon subsequent forward beats of the lay, the feed latch 73 is untouched, the feed pawl remaining in its set position ready to feed the hopper when it is permitted to do so by other conditions of the machine. When the feed pawl 60 is in set position, the feed latch 73 normally occupies its lowered or inoperative position, but when filling absence is indicated by the filling detector and the transerrer latch 36 is raised, a pin 86 inside of the latch engages the feed latch 73 and lifts it into operative position, so that whenever the transerrer is operated owing to the lifting of the bunter transerrer latch, both latches are presented to the bunter. As a result of this, when the bunter is forward, it engages both the transerrer latch and the feed latch, and while it is in forward position it holds the feed pawl operating lever 70 in the position shown in Fig. 5 so that the feed of the hopper does not take place until after the lay has retreated and the transerrer has risen, so there is no impingement of a bobbin against the face of the transerrer. The arm 67 of the feed pawl operating lever is provided with a downwardly extended projection 81 carrying upon its end a laterally extended stop dog 82 which is adapted to engage the butt recesses 83 of the butt-end disk 63, as indicated in Fig. 7, which shows the position of the parts after the feed of the hopper following a bobbin transfer. Thus it is seen that the engagement of the endmost bobbin with the abutment 84 is not relied upon to stop the advance movement of the hopper, but the advance movement of the hopper is positively determined by the engagement of the stop dog 82 with the advancing wall of the recess 83. The absence of bobbins does not interfere with the operation of the hopper. It is still fed, step by step, one bobbin space at a time, in order to advance the hopper to a position where a full bobbin, if there be any in the hopper, will be presented to the transerrer. The use of the stop dog 82 in the construction described secures this new mode of operation. Fig. 9 illustrates this operation. The bottom of the hopper is empty and consequently the feed pawl is set at each beat of the lay, and upon the back stroke of the lay the feed pawl advances the hopper one notch, the stop dog 82 preventing it from advancing more than one notch. At each time the feed pawl rises it swings the feed latch forward and thereby lifts it into position to be engaged by the bunter on the lay. This operation continues until the feed of the hopper by the feed pawl is prevented by the engagement of a bobbin with the abutment 84. With the parts in the position illustrated in Fig. 9, the feed pawl 60 has just been raised by its spring, thereby completing a feeding stroke 130

and at the same time swinging the feed latch 73 forward and raising it into position to be struck by the dagger on the lay. It is apparent that with two bobbin spaces 5 empty at the bottom of the hopper, as shown, the hopper will be racked forward two spaces before the bobbin 85 strikes the abutment 84 whereupon the bunter will strike the feed latch and lower the feed 10 pawl to set position, and then the feeding of the hopper will cease for the time being.

The stop pawl 90, provided with the tooth 91, is pivotally supported upon the hub 86 of the feed pawl operating lever 70, in turn 15 supported upon the stud 71 mounted in the hopper plate 5. The stop pawl 90 is provided with a hand hold 92 which projects outward away from the butt-end disk 63 and is adapted to be engaged by the hand 20 of the operative in order to lift the pawl off the rack 62. The feed pawl 60 and the stop pawl 90 are independent of each other. The feed pawl may be lifted off of the rack 62 without disturbing or touching the stop pawl 25 90. So also the stop pawl 90 may be withdrawn from engagement with the rack 62 without movement of or interference with the feed pawl 60. Like the feed pawl 60 a stop pawl 90 is provided with the projection 30 93 which projects toward the butt-end plate 63 and enters the space inside the ratchet 62. So the stops 64 and 93 respectively prevent the feed pawl and stop pawl from being moved so far as to cause either to engage 35 and lift the other pawl. The two projections or hand holds 65 and 92 are located near each other so that it is convenient for the operative to engage both with the hand so that both may be lifted from the ratchet 40 62 at the same time without there being any mechanical connection between the two pawls.

The small-end disk 100 supports the bobbin tips. The disk is provided with a hub 45 101 mounted on the stud 102 which supports the hopper, said stud being mounted in the hopper plate 5 and secured therein by the set screw 103. The disk 100 is provided with slots 104 which afford provision for supporting the tip springs 105 in place. These springs are loose steel springs of the shape shown in Fig. 2, each having a grooved tip holding projection 106 near its end. At the inner end of each spring is a hole which 50 receives the pin 107 projecting outwardly from the disk. The springs are sprung in place and held by their elasticity in position. The bobbins are inserted in the hopper by putting their butts in the recesses 83 within 55 the lip 110 of the hopper plate 5 and by placing the tip against the projection 106 on the end of the spring and forcing the bobbin tip over the projection against the portion 111 of the disk. The lip 110 extends 60 from the lower part of the front of the plate

5 around the periphery of the plate well toward the abutment where it terminates, as seen in Figs. 3, 4, 5, 7 and 9.

This brings us to the yielding bobbin support, which will now be described. The lip 70 110 co-operates with the recesses 83 to hold the butts of the bobbins in place in the butt-end disk. At the bottom of the hopper where the bobbin is discharged from the hopper by being moved radially out of it by the transfer, the lip 110 is omitted, but here the bobbins are prevented from falling or being jarred out of the recesses 83 by the yielding bobbin support 112 which consists of a strip of metal having a rounded or bent 80 end, as seen in Figs. 3, 5, 7 and 9, adapted to engage the butt of a bobbin at the time it is being transferred from the hopper to the shuttle. The body of the bobbin support is flat and extends rearwardly, being supported in the space 113 in the block 114 on the lower side of the hopper plate 5. The rear end of the bobbin support is upturned at 115 and a spring 116 engages such rear end and normally presses it forward into the position shown in the drawings, while permitting it to be moved rearwardly to compress the spring when a bobbin 85 is removed from the hopper. A cover plate holds the device in its cavity in the block 114. This bobbin support is, in a sense, a continuation of the lip 110 of the hopper plate 5, and has capacity to yield in a direction away from the abutment 84 so as to permit the escape of the bobbin from the 90 hopper.

The abutment and the bobbin support, together with the transfer 30 and tip depressing arm 117, comprise the means for moving and guiding the bobbin from the 105 hopper into the shuttle, and an additional means for securing the correct placing of the bobbin in the shuttle is found in the tip holder, as it is called. In inserting a bobbin in the shuttle the resistance offered to 110 the insertion of the bobbin by the spring clamp which engages the butt of the bobbin is sometimes such as to cause an accidental displacement of the bobbin in the shuttle from its correct position. Sometimes the 115 tip of the bobbin is so far depressed as to project below the surface of the lay. It is desirable, therefore, to provide means for supporting the tip of the incoming bobbin during the time it is being inserted in the 120 shuttle. The means which has been provided for accomplishing this purpose is described as follows:—Upon the end of the stud 33, which supports the transfer, is mounted the tip holder arm 120 which is a 125 rigid arm secured by the set screw 121 to the stud 33. This arm projects in a general downward and rearward direction from the stud 33 and is provided at its end with a hole 122 which receives the tip holder 123 130

which is slidably mounted in the hole 122. The tip holder 123 is provided in its front end with a hole which receives the lower end of a spring 124 which is secured to the arm 5 120 and resiliently presses the tip holder 123 into the position illustrated in Fig. 9 of the drawings. When a full bobbin is to be transferred from the hopper to the shuttle, it is forced downward by the transerrer 10 and itself displaces the spent bobbin to be removed from the shuttle, forcing it downward. At this time, of course, the lay is forward and the tip holder 123 projects under the shuttle, so when the spent bobbin first 15 emerges from the shuttle its tip hits the tip holder 123 and is prevented thereby from immediately falling or from being driven with high velocity away from the shuttle and the tip end of the spent bobbin is in 20 position to be engaged by the tip of the bobbin being inserted. It thereby prevents the tip of the new bobbin being inserted from being depressed beyond a point from which it will spring back into proper position in 25 the shuttle. The tip holder 123 is arranged as described so as to yield in case anything should be driven against its end by the lay, as, for example, the picker stick. In the 30 claims the word "shuttle" is to be taken and understood as comprehending any sort of equivalent device for introducing the filling into the shed; the word "bobbin" comprehends any sort of filling carrier; "hopper" includes any kind of filling carrier reservoir; 35 "transerrer" defines anything that transfers filling from the reservoir to the shuttle equivalent, and, similarly, other words are used as words of description and not of limitation except when the context necessarily 40 forbids.

Having thus described the illustrated embodiment of the invention and the mode of operation of the several parts in connection with the description of each, it is to be 45 pointed out that the invention is not limited to the illustrated embodiment, as it may be embodied in other forms within the scope of the following claims.

I claim—

50 1. An automatic loom having, in combination, a filling detector, filling supply mechanism including a latch lifter, a shuttle feeler for feeling for the shuttle while it is in the filling supply shuttle box, a lifter 55 operating arm for operating the shuttle feeler and the latch lifter, a hopper arm, connections between the hopper arm and the filling detector, said hopper arm being normally in contact with but disconnected 60 from the lifter operating arm, and a spring for holding the hopper arm in contact with the lifter operating arm except when the shuttle feeler strikes a shuttle.

65 2. An automatic loom having, in combination, a filling detector, filling supply

mechanism, a shuttle feeler, and connections between the shuttle feeler and the filling detector including a hopper arm, a latch lifter operating arm, a link connecting the shuttle feeler and the latch lifter operating 70 arm, a movable extension plate on the hopper arm having an inclined face engaging the latch lifter operating arm, and yielding connections between the latter and the extension plate.

75 3. An automatic loom having, in combination, a hopper, a transerrer, a lay, reciprocal means having provision for being supported in operative position by a spring and for being actuated thereby to 80 advance the bobbins in the hopper step by step to a position to be operated upon by the transerrer so long as a bobbin is absent from said position, and means for compressing the spring, said means being arranged to operate without a corresponding operation of the transerrer and being articulated with the reciprocal means, and having provision for engagement by the lay.

85 4. An automatic loom having, in combination, a hopper, a transerrer, a lay, a reciprocal feed pawl for advancing the bobbins in the hopper whenever a bobbin is absent from the position to be operated upon by the transerrer, a spring, a feed 90 pawl lever, and a latch, the spring serving to actuate the feed pawl in one direction, and the feed pawl lever and latch serving to actuate the feed pawl in the opposite direction without a corresponding actuation 95 of the transerrer, said latch having provision for engagement by the lay.

100 5. An automatic loom having, in combination, a filling detector, filling supply mechanism, a shuttle feeler for feeling for the shuttle while it is in the filling supply shuttle box, connections between the filling detector and the feeler and the filling supply mechanism comprising a hopper arm having a movable inclined face piece, means for 105 adjusting the face piece so as to cause different portions of the face to engage the part connected with the feeler and filling supply mechanism, and connections between the face piece and the part of the filling 110 supply mechanism the face piece engages.

115 6. An automatic loom having, in combination, a filling detector, filling supply mechanism, a shuttle feeler for feeling for the shuttle while it is in the filling supply shuttle box, a rock shaft operatively connected at one end to the filling detector and provided on its other end with a hopper arm having an adjustable portion adapted to be adjusted longitudinally of the arm, 120 and connections between the adjustable portion of the hopper arm and the feeler and filling supply mechanism.

125 7. An automatic loom having, in combination, a transerrer, a hopper, a latch, a 130

- latch lifting arm, the latch being operatively actuated upon by the latch lifting arm, and means operated by the latch and the lay for advancing the bobbins in the hopper step by step to be operated upon by the transferrer so long as a bobbin is absent from the position to be operated upon by the transferrer, whether or not there is a corresponding actuation of the transferrer.
10. An automatic loom having, in combination, a hopper, a transferrer, a latch, a latch lifting arm, the latch being lifted by the latch lifting arm, means operated upon by a spring for advancing the bobbins in the hopper step by step to be acted upon by the transferrer so long as a bobbin is absent from the position to be operated upon by the transferrer, and means exclusive of the transferrer operated upon by the lifting of the latch and the forward beat of the lay for compressing the spring.
15. An automatic loom having, in combination, a hopper, a transferrer, a feed pawl lever, a spring, and reciprocatory means operatively supported by the spring and the feed pawl lever for advancing the bobbins in the hopper step by step to a position to be acted upon by the transferrer without a corresponding actuation of the latter, so long as a bobbin is absent from said position, the lever serving to actuate the reciprocatory means in one direction and the spring serving to actuate it in the other direction.
20. An automatic loom having, in combination, a hopper, a transferrer, a lever, a spring, and reciprocatory means arranged for actuation without a corresponding actuation of the transferrer, operatively supported by the spring for advancing the bobbins in the hopper to a position to be acted upon by the transferrer, the lever serving to actuate the reciprocatory means in one direction and the spring serving to actuate it in the other direction, said lever having provision for preventing the hopper from advancing more than one bobbin space at each actuation of the bobbin advancing means.
25. An automatic loom having, in combination, a transferrer, a hopper provided with a ratchet, a reciprocatory feed pawl arranged for actuation without a corresponding actuation of the transferrer, operating with the ratchet to feed the hopper, a spring operatively connected with the pawl to actuate it in one direction, and means independent of the transferrer for compressing the spring to bring the pawl to a position to be actuated, said means having provision for preventing the pawl from feeding the hopper more than one bobbin at each actuation of the spring.
30. An automatic loom having, in combination, a hopper, a transferrer, and means arranged to be actuated without a corresponding actuation of the transferrer for advancing the bobbins in the hopper step by step to a position to be operated upon by the transferrer so long as a bobbin is absent from said position, and means connected with the hopper actuating means for locking the hopper after it has been moved through one bobbin space.
35. An automatic loom having, in combination, a hopper, a transferrer, and feeding means for the hopper operative only on the return beat of the lay to advance the hopper, said feeding means being arranged to advance the hopper without a corresponding actuation of the transferrer until a bobbin is in position to be operated upon by the transferrer.
40. An automatic loom, having, in combination, a hopper, a feed pawl for advancing the hopper, a feed pawl operating lever, a feed latch connected with the feed pawl operating lever, a transferrer, a transferrer latch, and a bunter for actuating the feed latch and the transferrer latch, said feed latch being constructed and arranged so that it may be actuated by the bunter without a corresponding actuation of the transferrer latch.
45. An automatic loom having, in combination, a lay, a hopper, a transferrer, and means including a feed pawl, for advancing the bobbins in the hopper step by step to a position to be operated upon by the transferrer whenever a bobbin is absent from said position, a feed pawl operating lever, and a feed latch lever, said feed pawl operating lever and latch lever being arranged for actuation by the lay without a corresponding actuation of the transferrer.
50. An automatic loom having, in combination, a lay, a transferrer, means for actuating it, a hopper, a reciprocatory feed pawl for feeding the hopper until a bobbin is in position to be operated upon by the transferrer, and means including a spring for reciprocating the pawl by the lay and the spring without a corresponding actuation of the transferrer.
55. An automatic loom having, in combination, a lay, a transferrer, a hopper provided with a ratchet, a pawl for engaging the ratchet to feed the hopper whenever a bobbin is absent from the position to be operated upon by the transferrer, a pivoted feed pawl operating lever articulated with the pawl, and a latch lever operatively connected with the feed pawl operating lever, the feed pawl operating lever being actuated by the latch lever to operate the pawl when the latch lever is moved forward by the lay on its forward beat, said feed pawl operating lever and latch lever being arranged to be actuated without a corresponding actuation of the transferrer.

18. An automatic loom having, in combination, a hopper provided with a ratchet, a pawl, means for moving the pawl in the direction to feed the hopper, and means for moving the pawl in the opposite direction having provision for preventing the feeding movement of the pawl during the operation of the transferrer. 18
19. An automatic loom having, in combination, a hopper, means for advancing the hopper to bring filling supply to a position to be operated on by the transferrer, and a stop dog engaging the butt-end recesses in the butt-end disk to prevent the hopper from advancing more than one step at a time. 19
20. An automatic loom having, in combination, a hopper, a feed pawl, a stop pawl for preventing backward rotation of the hopper, and a stop dog engaging the butt-end recesses in the butt-end disk for preventing more than a one-space feed of the hopper. 20
21. An automatic loom having, in combination, a hopper provided with a ratchet, a feed pawl for engaging the ratchet and advancing the hopper, a stop pawl for preventing backward movement of the hopper, means for disengaging the feed pawl from the ratchet, means for limiting the disengaging movement of the feed pawl from the ratchet to prevent the disengagement of the stop pawl from the ratchet by the stop pawl while the latter is disengaged therefrom. 21
22. An automatic loom having, in combination, a hopper, a transferrer, a hopper feed, and means separate from the transferrer for preventing the hopper feed from taking place after a weft replenishing operation until after the return stroke of the transferrer. 22
23. An automatic loom having, in combination, filling supply mechanism, a transferrer, feeding mechanism for the supply mechanism having provision for operating it step by step if a bobbin is absent from the position to be operated upon by the transferrer, and for preventing over-running of the supply mechanism during continued weaving operation of the loom whether or not there is a corresponding actuation of the transferrer. 23
24. An automatic loom having, in combination, filling supply mechanism, a transferrer, feeding mechanism for the supply mechanism having provision for operating it step by step and for preventing over-running of the supply mechanism on every beat of the lay until a bobbin is in position to be operated upon by the transferrer, whether or not there is a corresponding actuation of the transferrer. 24
25. An automatic loom having, in combination, filling supply mechanism, a trans- 25
- 5 ferrer, and feeding mechanism for the supply mechanism having provision for operating it step by step until a bobbin is in position to be operated upon by the transferrer, and for preventing over-running of the supply mechanism whether or not the transferrer is operated. 70
- 6 26. An automatic loom having, in combination, filling supply mechanism, a trans- 75
- 10 ferrer, and feeding mechanism for the supply mechanism having provision for operating it step by step and for preventing over-running of the supply mechanism when filling supply is absent from the position of presentation to the transferrer, said operation of the feeding mechanism occurring whether or not there is a corresponding actuation of the transferrer. 80
- 15 27. An automatic loom having, in combination, filling supply mechanism, a trans- 85
- 20 ferrer, and feeding mechanism for the supply mechanism having provision for operating it step by step and for preventing over-running of the supply mechanism so long as the loom runs and until filling supply occupies the position of presentation to the transferrer, said operation of the feeding mechanism occurring whether or not there is a corresponding actuation of the transferrer. 90
- 25 28. An automatic loom having, in combination, filling supply mechanism, a trans- 95
- 30 ferrer, and feeding mechanism for the filling supply mechanism having provision for operating it step by step and for preventing over-running of the supply mechanism when filling supply is absent from the position of presentation to the transferrer, whether the transferrer is operated or not. 100
- 35 29. An automatic loom having, in combination, a hopper provided with a butt-end disk having recesses to receive the butts of bobbins, and a small-end disk spaced approximately a bobbin length therefrom, provided with springs for engaging and holding the tips of the bobbins, such springs being supported and held in place by such slots, by pins and by their own resilience reinforced by a part of the hopper situated on the opposite side from that part of the hopper limiting the inward movement of their free ends. 105
- 40 30. An automatic loom having, in combination, a hopper provided with a butt-end disk having recesses to receive the butts of bobbins, and a small-end disk spaced approximately a bobbin length therefrom provided with springs and a series of radial slots each spanned by two bridges constituting spring holders for holding the springs 110
- 45 115 in position in the slots. 120
- 50 31. An automatic loom having, in combination, a transferrer, a hopper, a ratchet on the hopper, a feed pawl in engagement with the ratchet, a feed pawl operating lever ar- 125

- ranged to operate without a corresponding operation of the transfferer for actuating the feed pawl in one direction, a spring for actuating the lever in the opposite direction to advance the hopper, and a stop dog on the feed pawl operating lever for engaging the hopper and preventing it from moving more than one bobbin space at each spring-actuated movement of the feed pawl.
- 10 32. An automatic loom having, in combination, a transfferer, a hopper, a ratchet on the hopper, a feed pawl in engagement with the ratchet, means operating without a corresponding operation of the transfferer for actuating the feed pawl to advance the hopper, and means on the feed pawl actuating means having provision for engaging the hopper to prevent it from moving more

than one bobbin space at each actuation thereof by the feed pawl.

33. An automatic loom, having, in combination, a hopper, a feed pawl for advancing the hopper, a feed pawl operating lever, means for actuating the feed pawl operating lever, and a stop dog fixed on the feed pawl operating lever arranged so that it is brought into engagement with the hopper when the hopper is advanced to prevent the hopper from moving through more than a predetermined space at each advancement thereof.
